UNITED STATES PATENT OFFICE.

JOHN FAUST, OF BALTIMORE, MARYLAND.

CONSTRUCTION AND OPERATION OF ORDNANCE.

SPECIFICATION forming part of Letters Patent No. 534,214, dated February 12, 1895.

Application filed December 22, 1894. Serial No. 532,659. (No model.)

To all whom it may concern:

Be it known that I, JOHN FAUST, a citizen of the United States, residing at Baltimore, in the State of Maryland, have invented certain new and useful Improvements in the Construction and Operation of Guns, of which the following is a specification, reference being had therein to the accompanying drawings.

10 My invention relates to an improvement in the construction and operation of ordnance; and it has for its object the peculiar construction of the gun and its mounting, whereby the muzzle of the gun can be elevated or depressed or the gun swung horizontally in the arc of a circle in a convenient and easy manner.

15 The invention consists in a gun having a downwardly-projecting stem on which the trunnions and a cogged segment are formed, a pedestal in which the trunnions are mounted, a worm-gear carried by the pedestal and engaging with the cogged segment, means for operating said worm-gear, a base-plate on 20 which the pedestal is revolubly mounted, and means for turning the pedestal.

25 Figure 1 of the drawings is a vertical side elevation of a gun constructed and mounted in accordance with my invention. Fig. 2 is also a vertical side elevation of the same with the pedestal and base-plate in section, showing the various operating mechanisms. Fig. 3 is a side elevation of the gun removed from its mounting.

30 In the drawings, A represents the gun, on the lower side of which is cast a stem B, which carries the lateral trunnions C and a cogged segment D, the trunnions and segment being preferably formed integral with the stem.

35 E is a pedestal, which is recessed, as at e, to receive the cogged segment D, as shown in Fig. 2, the trunnions C resting in suitable bearings e' in the upper end of the pedestal, 40 they being held securely therein by metal straps e².

45 F is a worm-gear, adapted to engage with the cogs on segment D, said worm-gear being located in a recess f in the pedestal immediately beneath the recess e. The worm-gear

is mounted on a shaft F', journaled in the pedestal as shown; and provided with a hand-wheel f'.

In the lower portion of pedestal E is revolubly mounted a shaft G, on which, close to the pedestal, is rigidly fixed a gear-wheel H, for a purpose hereinafter stated, said shaft being also provided with a hand-wheel g.

I is a circular base-plate, rigidly secured to any suitable carriage, as J. In the center of this plate there is a socket i, to receive a stud e³ projecting from the bottom of the pedestal; and in the upper surface of the plate there is formed an annular groove i', adapted to receive a number of metal balls K, which have their bearing therein and also in a corresponding groove e⁴ formed in the underside of the pedestal.

I' is a cogged rack arranged in circular form on the base-plate I, it being preferably formed integral therewith, said rack being so arranged that the gear-wheel H will mesh with it, whereby as shaft G is turned the pedestal and the gun mounted thereon will be caused to swing horizontally in the arc of a circle.

55 From the description above given, taken in connection with the accompanying drawings, the various manipulations of the gun will be apparent.

Having thus described my invention, what I claim as new, and desire to secure by Letters Patent, is—

1. The combination, with a gun having a downwardly-projecting stem carrying the trunnions and a cogged segment, of a pedestal in which the trunnions are mounted, a worm-gear carried by the pedestal and engaging with the cogged segment, means for operating said worm-gear, a base-plate on which the pedestal is revolubly mounted, and means for turning the pedestal.

2. The combination, with a gun having a downwardly-projecting stem carrying the trunnions and a cogged segment, of a pedestal in which the trunnions are mounted, a worm-gear carried by the pedestal and engaging with the cogged segment, means for operating said worm-gear, a shaft revolubly mounted in the lower portion of the pedestal

and carrying a fixed gear-wheel, means for turning said shaft, a base-plate provided with ball-bearings on which the pedestal is revolvably mounted, and a circular cogged rack on the base-plate with which said gear-wheel is adapted to engage, substantially as described and for the purposes set forth.

In testimony whereof I affix my signature in presence of two witnesses.

JOHN FAUST.
